TRANSFER BIT, TRANSFER BIT BLANK AND METHOD OF PRODUCING THE BIT

Walter Larkin, Norristown, Pa., assignor to Fidelity Machine Company, Inc., Philadelphia, Pa., a corporation of Pennsylvania

Application March 18, 1955, Serial No. 495,262

13 Claims. (Cl. 66—95)

This invention relates to improvements in circular knitting machines of the type comprising dial-mounted transfer bits which function with the cylinder needles to produce a loop in the knitted fabric, in the form, for example, of a turned welt at the top of women's hose. Machines of this type are widely used in the industry for production by automatic operation of women's stockings of the turned-welt class, and their construction and mode of operation are well understood.

The present invention has for a primary object the provision of a circular knitting machine of the aforesaid type capable of producing turned-welt stockings in fabrics of finer gauge than was considered practicable prior to this invention.

To this primary end, the invention contemplates the provision of a transfer bit of improved structural design exhibiting materially greater strength, rigidity, durability and compactness than the corresponding bits of the prior art.

Another object is to provide a transfer bit of integral form—as compared with the prior conventional composite or two part bits, and which by reason of its novel construction will not only exhibit improved functional characteristics in itself but will also confer materially improved characteristics on the machine in which it may be employed, as hereinafter fully described.

In the attached drawings:

Fig. 1 is a fragmentary sectional view of a knitting machine of the type to which the invention relates comprising a dial in which are mounted bits made in accordance with the invention;

Fig. 2 is a face view of a blank of a character from which the bit may be formed;

Fig. 3 is a top edge view of the blank;

Fig. 4 is a side view of the finished bit;

Fig. 5 is a top edge view of the bit, and

Fig. 6 is an exploded perspective view showing the two separate parts of a conventional composite bit.

With reference to the drawings, the fragmentary part of the knitting machine shown in Fig. 1 comprises the usual needle cylinder 1; a dial 2, which carries in the lower member 2a thereof the transfer bits to which the present invention primarily relates; and a conventional sinker ring 3. The dial 2 has the usual radial slots in which the transfer bits 4 are mounted in conventional manner, and each of the bits has an actuating butt 5 which is engaged in a cam groove 6 in the upper or cap member 2b for projecting and retracting the bits 4 in known manner. The sinker ring 3 carries sinkers 7 which function in conjunction with the cylinder needles 8 in accordance with the usual practice. This mechanism, including the transfer bits 4, operate to produce a loop or turned welt, indicated at 9, in the knitted fabric, in manner well known in the art.

The transfer bit forming the subject of the present invention is illustrated in Figs. 4 and 5. In general, it conforms in shape and function to the corresponding bits of the prior art, having a needle-receiving eye 11 adjacent the forward or working end the forward wall of which is

2

divided vertically as indicated at 12, and comprising also an adjoining yarn-retaining terminal hook 13 which functions in known manner. The rear body portion 14 of the bit, embracing in the present instance approximately one-half of the overall length of the bit, carries at its forward end the bit-actuating butt 5 previously referred to. When in the normal operation of the bits the loops of the fabric 9 carried on the hooks 13 are to be transferred to the needles 8, the bits are projected to the position shown in Fig. 1 wherein the eyes 11 are aligned with the needles 8. The latter are then elevated beyond their normal knitting range so as to pass upwardly through or into the eyes as illustrated, the bits are retracted, and the needles, passing through the divided forward wall 12 of the eye, pick up and withdraw the loops from the hooks 13.

In accordance with the present invention, the rear or body portion 14 of the transfer bit is of integral formation, being formed from metal of the desired ultimate gauge or thickness, or forged to said thickness from a single piece. This portion of the bit comprises the butt 5 as an integral part thereof. The forward portion 16 of the bit is composed of relatively thin metal also integral with and approximately one-half the thickness of the body portion 14, so that when this portion is folded once upon itself, as described below, the thickness of the forward portion of the bit will correspond to that of the said body portion. In its original blank form, the forward portion of the bit is shaped as shown in Figs. 2 and 3 with a generally diamond shaped recess 21 in its forward edge forming bifurcations 22 and 23. These bifurcations are offset in part from the plane of the blank to form aligned recesses 24 and 25, and the forward edge of one of the bifurcations has an extension which constitutes the hook 13. This blank is folded along a line indicated in Fig. 2 by the reference numeral 26, the line being parallel in the present instance to the longitudinal centerline of the bit, and when so folded the bifurcations 22 and 23 and their respective recesses 24 and 25 register to form the eye 11 having the divided forward wall 12 as previously described, the extension 13 forming the hook 13 immediately adjoining the said forward wall.

It will be noted that the folding of the metal along the line 26 forms an upper reinforced edge extending over a substantial part of the length of the forward portion of the bit, the said edge being in the nature of a backbone which confers strength and rigidity on the laminar forward portion. This rib, however, terminates sufficiently short of the rear wall of the eye 11 to afford the required flexibility in the confronting portions at the opposite sides of the eye 11 to permit the separation at the division of the forward wall for passage through that wall of the needle 8 when the bit is retracted as described above.

There are material advantages accruing to a bit of this construction as compared with those bits of the prior art composite of two strips of metal of the character shown at 26 and 27 in Fig. 6. In that case, each of the parts 26 and 27 carried an actuating butt 28 and 29 respectively which operated jointly in the cam slot of cap 2b of the dial to actuate the composite bit. Since the strips are necessarily thin, these butt elements 28 and 29 were individually relatively weak and incapable in themselves of withstanding the stresses involved in the actuation of the bit. Since the two parts of the bit are subject after slight wear to relative longitudinal displacements, the major part of the thrust of the cam was received eventually by one or other of the butt elements 28 and 29, and by reason of the relative weakness of the individual element there was a tendency for that half of the bit to fracture, usually at the juncture of the side edge of the butt with the top edge of the strip. To avoid this inherent weakness it was necessary to use a relatively heavy gauge of metal in each of the two parts, and as a result the over-

all thickness of the bit was relatively great. This fact imposed a definite limit on the number of such bits that could be mounted in a dial of given diameter and, indirectly, imposed a similar limitation on the number of needles which could be used in the cylinder in this type of knitting machine.

Another disadvantage of the prior construction resided in the fact that the individual bit elements 26 and 27 being relatively thin were also relatively lacking in rigidity and required support over a great part of their length particularly when projected to the extended position required for the transfer operation. Without such support, the bits lacked the stability required for trouble-free operation, being liable to interfere with and to cause damage to the needles and to the machine. In order to provide adequate support for the bits it was necessary to extend the dial radially and to place the dial in a position relatively remote from the upper end of the needle cylinder in order to maintain space in the throat where adequate clearance is essential to proper functioning of the machine.

A primary advantage of the bit provided by the present invention resides in the integral construction. The strength of a solid piece of metal, as in the body portion and butt, is materially greater than the strength of two separate and contiguous pieces of corresponding joint thickness. The overall thickness of the body portion of the bit can be made relatively thin as compared with the overall thickness of aforesaid composite bits of the prior art without sacrifice of essential strength, particularly in the butt area. This relative compactness permits the use of a larger number of bits in a dial of given diameter, and a corresponding increase in the number of needles in the cylinder. The invention, therefore, extends the utility of machines of this class into the field of the finer gauge fabrics.

The tendency for fracture at the base of the butt 5 is largely avoided in that even with the reduction in overall thickness of the bit, the strength of the solid butt is relatively great as compared with the individual butt elements of the composite bit described above. The machines, therefore, may be operated at relatively high rates of speed under trouble-free conditions.

The integral folded laminar forward portion of the bit also confers material advantages. As described, the line of fold constitutes in effect a backbone of relatively great strength which adds materially to the rigidity of this forward portion of the bit without sacrificing essential flexibility in the bifurcations for separation of the split forward wall of the eye by the needle as described above. This increased strength and rigidity and the accompanying high degree of stability in the forward part of the bit not only permits trouble-free operation of the machine at the relatively high rates of speeds, but permits also an increase in the width of the throat between the periphery of the dial and the needle cylinder, this by reason of the fact that the bit when projected to the maximum extent still exhibits the relatively high degrees of stability and rigidity required for proper coaction with the knitting needles.

I claim:

1. In a transfer bit of the type comprising a needle-receiving eye having a divided forward wall, and an adjoining yarn-retaining terminal hook, an integral flat body portion extending longitudinally from the rear end of the bit and including a bit-actuating butt, said body portion terminating rearwardly of said eye, and a forward portion of relatively thin metal integral with the said body portion and folded on itself along a line between the said body portion and the eye, said folded portions having confronting free terminal parts forming the respective opposite sides of said eye, and one at least of said terminal portions having an extremity forming the said hook.

2. A transfer bit according to claim 1 wherein the said fold line lies at the upper edge of the forward portion of the bit.

3. A transfer bit according to claim 1 wherein said forward portion is joined to the body portion so that one side face thereof lies flush with and constitutes a continuation of one face of the body portion, and is folded so that another face of the forward portion is flush with the other side face of the said body portion.

4. A transfer bit according to claim 1 wherein the said free terminal portions have registering outwardly displaced sections forming the walls of said eye.

5. A transfer bit according to claim 4 wherein the said fold line terminates short of the wall of said eye so as to extend the effective length and to correspondingly increase flexibility of the free terminal portions.

6. A blank for transfer bits of the type described, said blank having at one end a flat body portion of given thickness having an integral projection from one edge providing an actuating butt for the finished bit, and an opposite end portion of lesser thickness than but integral with the body portion and having bifurcations at the end thereof remote to the body portion, said portion of lesser thickness being foldable on a line extending from the inner ends of the bifurcations to bring the latter into overlapping relation, and said bifurcations having recesses arranged to register in the said overlapped relation to provide a needle-accommodating eye for the finished bit.

7. A blank according to claim 6 including a terminal extension on at least one of said bifurcations providing a loop-retaining hook for the finished bit.

8. A blank according to claim 6 wherein each of the two end portions have one face in a common plane, and wherein the said body portion is substantially twice the thickness of the opposite end portion.

9. A blank according to claim 6 wherein the recesses in the bifurcations are constituted by local areas displaced from the common plane of the bifurcations.

10. In a blank for transfer bits of the type described, an integral metal strip having opposite ends of differing thickness, the end of lesser thickness being increased in height beyond the line of juncture with the thicker end and being bifurcated at its outer extremity so as to afford an upper longitudinal section adapted for folding over against the face of the lower section to produce a laminar end portion of substantially the same thickness as the said thicker end and having a split extremity formed by the confronting bifurcations.

11. A blank according to claim 10 wherein the end of greater thickness includes a projection at its upper edge providing an actuating butt for the finished bit.

12. The method of producing a transfer bit of the type described having combined strength and compactness, said method including the production of a blank having at one end a body portion of given thickness and comprising a butt-forming projection, and having an opposite end portion of lesser thickness with aligned recesses, and folding the latter end portion on itself to bring the said recesses into registration and to afford an effective thickness in that end portion corresponding to the thickness of the body portion.

13. A transfer bit of the type described having at one end a body portion formed of a single piece of metal and including a bit-actuating butt, and having an opposite end including a divided working tip and composed of relatively thin sheet metal integral with the body portion and folded on itself to afford an effective thickness corresponding approximately to that of the body portion.
